UNITED STATES PATENT OFFICE.

THOMAS E. NEW, OF CINCINNATI, OHIO, ASSIGNOR, BY DIRECT AND MESNE ASSIGNMENTS, TO THE TELEFORCE RADIO LABORATORIES COMPANY, OF CINCINNATI, OHIO, A CORPORATION OF OHIO.

RADIO APPARATUS.

Application filed May 27, 1925. Serial No. 33,276.

My invention relates to tuning units for radio receivers and the like.

An object of my invention is to provide a device wherein a multiplicity of individual tuning devices and circuits can be controlled by one tuning knob and dial.

Another object of my invention is to provide a device wherein several variable condensers and a vernier can be controlled with one knob.

Another object of my invention is to provide a device that is simple and economical of construction and operation to attain the above objects.

These and other objects are attained by the means described herein and disclosed in the accompanying drawings, in which:

Fig. 1 is an elevational view of a device embodying my invention, partly shown in cross section.

Fig. 2 is a top plan view of the device shown in Fig. 1.

Fig. 3 is a sectional view taken on line 3—3 of Fig. 1.

Fig. 4 is a sectional view taken on line 4—4 of Fig. 3.

Fig. 5 is a wiring diagram of a radio circuit having embodied therein a device of my invention, the device being shown conventionally.

In a radio receiving set employing two or more variable condensers it is often necessary to advance one of the condensers through a part of its arc and then advance the other condenser through a greater portion of its arc in order to get a satisfactory result. The device of my invention obviates this dual manipulation yet accomplishes the same results. My device comprises, generally, a frame 10, variable condensers 11 and 12 and a vernier 13. The frame consists of a front plate 14 and rear plate 15 having secured between them side bars 16. The front and rear plates 14 and 15 have formed in them, in axial alignment, perforations 17 and 41, through which a shaft 18 extends. Rotor plates 19 and 20 of the condensers 11 and 12 are carried in spaced relation by the shaft 18, the usual spacing collars 21 being employed to space the rotor plates 19 and 20. A sleeve 42 carried by shaft 18 is used to separate the condensers 11 and 12 one from the other. A graduated dial 48 may be mounted on the end of shaft 18. The rotor

plates 19 and 20 are electrically connected 55 through the shaft 18. The stator plates 22 and 23 of the condensers 11 and 12 are not electrically connected. The stator plates of the respective condensers may be soldered to an L-shaped binding plate 24 or they may 60 be electrically connected in any other manner. Binding plates 24 have mounted on them binding posts 25. The stator plates 22 and 23 are carried by and are insulated from cross bars 16 by insulators 26. The 65 insulators 26 securely hold and retain the stator plates of the condensers 11 and 12 in position. The front and rear plates 14 and 15 are provided with extensions 27 and 28. The extensions 27 and 28 have formed 70 in them in axial alignment, perforations 29 and 43 through which shaft 30 extends. The rotor plates 31 of the vernier 13 are carried by the shaft 30 in spaced relation. The rotor plates 31 of the vernier 13 comprise a central hub 44 having vanes 45 and 46 extending from the hub diametrically opposite one another. Certain of the stator plates 19 of the condenser 11 extend below the condenser proper and constitute 80 the stator plates 32 of the vernier 13. The special object of the vernier will be explained later.

Front plate 14 has formed in it, intermediate perforations 17 and 19, a third perforation 33 in axial alignment with a perforation 34 formed in bearing bar 35. The bearing bar 35 is carried by the front plate 14. A stud shaft 36 having a knob 37 mounted on its front end extends through 85 perforations 33 and 34. A nut or collar 47 is provided on the rear end of stud shaft 36 to secure the stud shaft in place. Stud shaft 36 has mounted on it a gear 37 and a pinion 38. The gear 37 meshes with a pinion 39 carried by one end of shaft 30. A gear 40 carried by shaft 18 meshes with pinion 38 carried by shaft 36. It should be noted that by using the proper ratio between gear 37 and pinion 39 and pinion 38 and gear 40 95 it is possible to rotate the rotor plates of the vernier 13 a number of times while the rotor plates 19 and 20 are being rotated but once. It should also be noted that the rotor plates 31 of the vernier 13 are electrically connected with the rotor plates 19 and 20 through the shaft 18, gears 37 and 40, pinions 38 and 39 and shaft 30. 100 105

In order to make my invention clear and to explain the operation thereof, we will assume the shaft 30 bears a ratio of 20 to 1 to shaft 18. We will further assume that the capacity of condenser 11 is .0009 microfarad, that of condenser 12 .001 microfarad, and the vernier a capacity of .0002 microfarad. By using the ratio of 20 to 1 the shaft 30 will be revolved ten times while the shaft 18 makes but one-half of a revolution. The rotor plates 31 being mounted on the shaft 30 and the vanes 45 and 46 of the plates being spaced 180° apart, the vernier 13 would reach its maximum and minimum point of capacity twice in each revolution of the shaft 30, or twenty times while the rotor plates 19 and 20 of the condensers 11 and 12 pass from their minimum to their maximum point of capacity. In other words, the main condenser passes through its cycle but once while being actuated for attaining its maximum and minimum capacity while the vernier or secondary condenser passes through its cycle a number of times. The vernier or secondary condenser attains its maximum and minimum capacity during each cycle. It should be noted that the ratio between shafts 18 and 30 may be increased to effect a rapid turning of the rotor plates of the vernier or secondary condenser while the rotor plates of the main condensers are actuated through a very small portion of their cycle, thereby effecting a rapid changing of capacity in the condensers, and obtaining the true resonance of the primary condenser at practically any point in the cycle of the primary condenser. Owing to the difference in capacities between the two condensers 11 and 12, the maximum point of capacity, or true resonance, cannot be obtained from the two condensers at the same point on the dial. In order to bridge the gap between the condensers and to obtain true resonance, I introduce the vernier 13. Attention is directed to the fact that where ordinarily two separate condensers are tuned by separate control knobs to obtain the true resonance, I have accomplished the same result with but one control knob. It should therefore be noted that I have produced a single tuning unit composed of a multiplicity of ordinarily individually tuned devices.

Fig. 5 shows a wiring diagram for a radio receiving set employing a device of my invention. It is believed that the wiring diagram is self explanatory and further description is unnecessary.

What I claim is:

1. In a device of the class described the combination with a condenser comprising a movable and a fixed plate, of a second condenser comprising a movable and a fixed plate, one plate of the second condenser electrically connected with a plate of the first condenser, and means for effecting differen-

tial movement of the plates of the two condensers.

2. In a device of the class described the combination of a pair of electrically connected variable condensers each having a cycle for attaining maximum and minimum capacities, of means for simultaneously completing one cycle of one condenser and for repeatedly completing the cycle of the other condenser. 75

3. In a device of the class described the combination of a frame, a pair of condensers each comprising movable and fixed plates, the movable plates of one condenser mounted on a shaft, the movable plates of the second condensers mounted on a second shaft, the rotor plates being electrically connected, the fixed plates being mounted on and insulated from the frame, the fixed plates being electrically connected, and co-operating means carried by the shafts for effecting a rapid movement of the movable plates of one condenser to a slow movement of the movable plates of the other condenser. 85

4. In a device of the class described the combination of a frame, a plurality of primary condensers and a secondary condenser each comprising movable and fixed plates, the movable plates of the primary and secondary condensers being electrically connected, the stationary plates of one of the primary condensers and the stationary plates of the secondary condenser being electrically connected, the stationary plates being carried by and insulated from the frame, and means carried by the frame co-operating with means carried by the movable plates for effecting a differential movement of the movable plates of the primary and secondary condensers. 95 100 105

5. In a device of the class described the combination of a frame, a primary shaft and a secondary shaft carried by the frame, a plurality of primary condensers and a secondary condenser, each comprising fixed and movable plates, the movable plates of the primary condensers being carried by the primary shaft and the movable plates of the secondary condenser being carried by the secondary shaft, the fixed plates being carried by and insulated from the frame, the movable plates of the condensers being electrically connected, a stud shaft carried by the frame, means mounted on the stud shaft co-operating with means mounted on the primary and secondary shaft for effecting a differential movement of the movable plates, and means carried by the stud shaft for actuating the shafts. 110 115 120

6. In a device of the class described the combination of a primary tuning device for one circuit comprising a movable member, a secondary tuning device for a second circuit comprising a movable member, said primary and secondary tuning devices being related 125 130

whereby each may affect the other for bringing the two circuits into resonance, and a single means for simultaneously and differentially actuating the movable members of both tuning devices.

7. In a device of the class described the combination of a pair of tuning devices, each having a cycle and each comprising a movable member, electrical compensating means between said tuning devices whereby each device may affect the other device upon movement of the movable member of either, and means for differential completion of the cycles of the individual tuning devices.

8. In a device of the class described the combination of a pair of tuning devices each comprising a movable member so related that movement of either will affect both tuning devices, the movable members each having a cycle, and common actuating means for the movable members effecting differential completion of the cycles of the individual tuning devices.

In testimony whereof, I have hereunto subscribed my name this 20th day of May, 1925.

THOMAS E. NEW.
